UNITED STATES PATENT OFFICE.

BENJAMIN DICKENSON, OF NEW YORK, N. Y.

DEVICE FOR HOLDING HATS.

1,083,922.

Specification of Letters Patent.

Patented Jan. 13, 1914.

Application filed February 23, 1912. Serial No. 679,429.

To all whom it may concern:

Be it known that I, BENJAMIN DICKENSON, a citizen of the United States, and a resident of the city, county, and State of 5 New York, have invented certain new and useful Improvements in Devices for Holding Hats, of which the following is a full, clear, and exact specification.

My invention relates to improvements in 10 devices for temporarily holding hats or other articles, and especially to those used by women for securing their hats in trunks, wardrobes, etc., and the particular objects of my invention are to provide a device 15 which is easily removable from and replaced in or on the receptacle or support containing or holding it, and also to provide means for securely holding and locking it in place. I attain these objects by the device which I 20 have described in the accompanying specification and illustrated in the accompanying drawings, in which like symbols of reference refer to like parts throughout the respective views.

25 In some devices of this class which I have seen, the carrier has been either insecurely attached to the support, and so free to move, or else the parts necessary for securing it have taken up considerable space and been 30 in the way, besides being liable to distortion, breaking, and generally getting out of order. By my device, however, I am enabled to provide a means of rigid attachment, taking up very little room and easily manip- 35 ulatable, and unlikely to get out of order.

Figure 1 is an elevation, partly in section, of my hat carrier a part being broken away. Fig. 2 is a section of the base or stand with certain connected parts shown in elevation. 40 Fig. 3 is an inverted plan view of Fig. 2. Fig. 4 is a perspective view of the spring intended to secure and lock the hat carrier to the base.

In Fig. 1, 1 is a ball, or form, of more or 45 less globular shape, sometimes made of wire netting or cloth or other pervious material, which is stuffed with cotton, fiber, or other loose substance, and on which a hat is intended to be placed and secured by the insertion of pins. The cover of this ball is 50 intended to be placed over a shank or spool 2, provided with a flange on the top 3, a flange on the bottom 3' and a lug 4, projecting therefrom. The ball 1 may be secured 55 to the shank or spool 2 by means of wire or cord wrappings around the latter, the

flange 3 preventing the spool from being pulled out of the ball, and the whole being securely connected together.

The base 5, which may be of any convenient shape, is provided with a slot 10, extending approximately half way across its upper surface. This slot, for substantially its whole length, is of the same width as the diameter of the lug 4, but is enlarged 60 at its outer portion to permit the free insertion of the lug therein. The bottom of the lug 4 is enlarged to form a head or shoulder, which prevents it from being withdrawn vertically through the slot 10, 65 70 and also for another purpose to be mentioned hereafter.

Secured on the under side of the base 5 is a spring 6, riveted or otherwise secured at one end as at 7, and projecting through the 75 base in an aperture 11, which permits a certain amount of play or vertical motion to the spring. The spring ends in a projection 9, which enables it to be depressed at will. At a point directly beneath the slot 10, the 80 spring is provided with a depression or inclined face of such form that when the shoulder of the lug 4 impinges against it the spring will be automatically forced down by the motion of the lug 4, along the 85 slot 10, until the shoulder of the lug 4 has passed off the farther edge of the spring, when the latter snaps into place against the under side of the top of the base 5, and so prevents the retraction or slipping out of 90 the lug through the groove 10, until the spring is intentionally depressed.

When it is desired to remove the hat holding device from the base 5, the end of the spring 9 is pushed down, which results in 95 the spring itself being so lowered that the shoulder of the lug 4 can pass between the spring 6 and the lower surface of the upper part of the base 5, when the device can be removed through the groove 10.

I wish it to be understood that I do not limit myself to any particular form, substance, design, proportion or arrangement of the parts of my device, as these may be departed from in various ways without departing from the spirit of my invention. But

What I do claim as new herein and desire to protect by Letters Patent, is:

1. The combination of a pervious body; 110 a shank; means for securing the pervious body to the shank; a lug projecting from

the shank and having an enlarged shoulder; a base having a slot extending from its edge approximately to its center; a guard intersecting said slot and adapted to be displaced by the insertion of the lug in the slot, and adapted to resume its place behind the lug after the passage of the lug, to prevent the dislocation of the lug.

2. As a new article of manufacture, a hat carrier comprising a pervious body; a shank having an enlarged head enveloped by the pervious body, the exterior end of which shank constitutes a bearing surface adapted to bear and be supported against a base; a

lug projecting axially from the bearing surface and provided with an enlarged shoulder; a base provided with a slot in its upper surface against which surface the end of the shank is adapted to bear; and a spring secured to the base and lying transversely to the slot and adapted to be displaced by the insertion of the lug in the slot, and to retract behind the same to prevent its removal through the slot.

BENJAMIN DICKENSON.
